UNITED STATES PATENT OFFICE

154,859

DESIGN FOR AN EAR CLIP FINDING

Willis E. Kennison, Providence, R. I.; Louise M. Roberts administratrix of said Willis E. Kennison, deceased, assignor to Louise M. Roberts, Providence, R. I.

Application March 15, 1947, Serial No. 137,634

Term of patent 14 years

(Cl. D45—1)

To all whom it may concern:

Be it known that I, Willis E. Kennison, a citizen of the United States of America, residing at Providence, county of Providence, State of Rhode Island, have invented a new, original, and ornamental Design for an Ear Clip Finding, of which the following is a specification, reference being had to the accompanying drawing, forming a part thereof.

Figure 1 is a back elevation showing my new design for an ear clip finding; and

Figure 2 is a side elevation thereof.

The dominant part of the design is shown in full lines.

I claim:

The ornamental design for an ear clip finding, substantially as shown and described.

WILLIS E. KENNISON.
